UNITED STATES PATENT OFFICE

SAMUEL E. GUINN, OF JOHNSON CITY, TENNESSEE

DESIGN FOR A CIGAR LIGHTER

Application filed April 12, 1929. Serial No. 30,888. Term of patent 3½ years.

To all whom it may concern:

Be it known that I, SAMUEL E. GUINN, a citizen of the United States, residing at Johnson City, in the county of Washington and State of Tennessee, have invented a new, original, and ornamental Design for Cigar Lighters, of which the following is a specification, reference being had to the accompanying drawings, forming part thereof, and in which the figure is a perspective view of the cigar lighter.

I claim:

The ornamental design for a cigar lighter, as shown.

SAMUEL E. GUINN.
